CLAIM

The ornamental design for a footwear outsole, as shown and described.

DESCRIPTION

FIG. 1 is a perspective view of a footwear outsole showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The short broken lines shown directly on the outer surface of FIGS. 1–7 are understood to represent stitching. The longer segmented broken lines shown around the periphery of the inner surface of FIGS. 2, 4 and 5 represent the portion of the design that forms no part of the claim.
